(57) **CLAIM**

The ornamental design for a socket with power cord, as shown and described.

DESCRIPTION

FIG. 1 is a front elevational view of a socket with power cord showing our new design, the rear view being a mirror image thereof;

FIG. 2 is a top plan view thereof;

FIG. 3 is a bottom plan view thereof;

FIG. 4 is a left side view thereof;

FIG. 5 is a right side view thereof; and,

FIG. 6 is a perspective view showing the socket in association with a plurality of caps shown in broken lines.

The broken lines are shown for illustrative purposes only and form no part of the claimed design.

The cord is shown broken away to indicate an indeterminate length.
